(57) **CLAIM**

I claim the ornamental design for a biochemical analyzer, as shown and described.

DESCRIPTION

FIG. 1 is a front perspective view of a biochemical analyzer of the present invention;

FIG. 2 is a bottom perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof;

FIG. 8 is a bottom view thereof; and,

FIG. 9 is a bottom perspective view thereof shown in an environmental use.

The broken line showing of biochemical analyzer is included for the purpose of illustrating environment and forms no part of the claimed design.
